UNITED STATES PATENT OFFICE.

ISAAC M. BLANCHARD, OF NEW ALBANY, OHIO.

CORN-HARVESTER.

SPECIFICATION forming part of Letters Patent No. 689,949, dated December 31, 1901.

Application filed June 18, 1901. Serial No. 65,026. (No model.)

To all whom it may concern:

Be it known that I, ISAAC M. BLANCHARD, a citizen of the United States, residing at New Albany, in the county of Franklin and State 5 of Ohio, have invented certain new and useful Improvements in Corn-Harvesters; and I do hereby declare the following to be a full, clear, and exact description of the invention, such as will enable others skilled in the art 10 to which it appertains to make and use the same.

The object of this invention is to provide a simple, economical, and effective machine for cutting or harvesting corn.

15 The invention and the features of novelty are set forth and pointed out in the following description and claims.

In the accompanying drawings, illustrating one embodiment of my invention, Figure 1 20 is a vertical longitudinal sectional view, taken on line $x-x$ of Fig. 2, looking toward the inner left-hand side of the machine. Fig. 2 is a view in elevation of the rear end of the machine, one of the cutters being folded against the 25 side of the machine and the left-hand side being partially in section. Fig. 3 is a plan view looking down, one of the guards being broken off; and Fig. 4 is a detail in section illustrating the platform-elevating devices.

30 Like characters of reference in the several views designate corresponding parts.

The character 1 designates the carrying-wheels. There need be, and preferably are, but two of these wheels. 2 designates the 35 axle between these wheels, upon which all the parts are shown to be carried and supported.

3 is the platform, rising vertically from each side of which are large clevises 4, shaped to form vertical slots or guides through or in 40 which the axle 2 extends. One arm 4^a of each clevis is located forward of the vertical plane of the axle, while another, 4^b , is located in rear of the vertical plane thereof. A lever 5 is fulcrumed at one end to the forward arm 45 4^a of each clevis, while the other end extends to the rear of the machine, so as to be within easy reach of the operator. The rear arm or branch 4^b of the clevis is made with a number of holes 4^c , into which a pin 6 can be 50 passed to secure the lever with respect to the clevis. A hanger 7, secured to the lever and to the axle, suspends the platform from

the axle. By raising or lowering the rear ends of the levers 5 the platform is raised or lowered, and by placing the pin 6 in the proper hole 4^c the platform can be fixed in the position to which it is raised or lowered, the slot in the clevises 4 permitting such raising or lowering. It will be observed, therefore, that the platform is virtually pivotally suspended on the hangers 7 and is therefore capable of being tilted or inclined. Whether the platform shall be fixed to stand in a horizontal position will depend upon the nature of the work to be done and the circumstances 65 under which it is to be done. The platform can be fixed in a horizontal or inclined position by means of a bar 8, attached to the front end of the platform and reaching upward to the cross-bar on the shaft or pole of the machine. This bar 8 is made with a series of holes 8^a , through which and a hole in the cross-bar of the shaft or pole a pin 9 can be passed to secure the bar 8 from movement, and therefore determine the degree of inclination of the platform. It will thus be noted 70 that the platform is capable of two adjustments, one as to the vertical distance from the ground and the other as to its inclination with respect to the ground. 75

Hinged to the platform at each side of the machine and beyond the wheels is a wing 10, bearing at its forward edge a cutter or knife 11, the edge of which is shown when down in the cutting position to be inclined outwardly and rearwardly, so that when the machine is drawn forward through the corn it 80 cuts with a shear cut, and therefore with a more certain and effective action.

The machine shown is adapted to cut two 90 rows of corn at one time. In practice two men will stand back to back upon the platform and gather the stalks as fast as they are cut and before they can fall to the ground. The men each brace themselves by placing 95 one foot against a stirrup or projection 12 on the front of the platform and the other against the block or projection 13 on the rear of the platform. Guards 14 and 15 on the yoke 14 a will prevent the men from coming into contact with the wheels. Vertically-arranged guards 16, secured to the platform and yokes 14 a beyond the wheels, will serve to prevent the stalks from becoming entangled with the 100

wheels. When the soil is moist or there is a tendency of it to accumulate on the carrying-wheels, scrapers 18 can be moved into position to clear the wheels. These scrapers are shown to be on the rear ends of rods 18^a, and the forward ends of these rods are attached to cranks at the ends of a transversely-arranged rod 20 under the platform. This rod can be rocked or given a half-revolution by means of a weighted block 17, fixed to said rod, (see Figs. 1 and 3,) whereby the scrapers can be moved toward or from the position to remove the accumulation from the wheels. When the machine is not in operation, the knives or cutter-bearing wings can be turned up at the sides of the wheels and held in this position by a hook 19.

It will be observed that my machine is quite compact in its construction, is capable of nice 20 adjustments, and can be freely turned about short corners.

What I claim, and desire to secure by Letters Patent, is—

1. In a corn-harvester, the combination 25 with carrying-wheels and an axle, a hanger on said axle, a platform carrying cutters, a lever connected with the platform and the hanger for adjusting the platform vertically, a guide rising vertically from the platform 30 and engaging the axle, and means whereby the lever can be fixed in different positions, substantially as described.

2. In a corn-harvester, the combination 35 with carrying-wheels, an axle, a platform carrying cutters, a hanger on said axle, a lever connected with the platform and the

hanger for adjusting the platform vertically, means for preventing the horizontal movement of the platform with respect to the axle, and means for securing the lever in its different positions, substantially as described. 40

3. In a corn-harvester, carrying-wheels and an axle, a platform carrying cutters, a hanger on said axle, a lever connected with said hanger and platform for vertically adjusting 45 the platform, combined with means whereby the platform can be tilted, and fixed in tilted position, substantially as described.

4. In a corn-harvester, the combination 50 with the carrying-wheels and an axle, of a platform, slotted clevises 4 rising from said platform and engaging the axle, levers 5 pivoted to said clevises, hangers 7 suspending the platform through said lever, and means for securing said levers when adjusted, substan- 55 tially as described.

5. In a corn-harvester, the combination 60 with the carrying-wheels and axle, of a platform, slotted clevises 4 rising from said platform and engaging the axle, levers 5 pivoted 65 to said clevises, hangers 7 suspending the platform through said levers, means for securing said levers when adjusted, and a bar 8 for tilting said platform and means for securing the same, substantially as described. 65

In testimony whereof I affix my signature in presence of two witnesses.

ISAAC M. BLANCHARD.
